(57) **CLAIM**

The ornamental design for a thermometer, as shown and
described in the following Figures.

DESCRIPTION

FIG. 1 is a perspective view of a thermometer of the present
invention;

FIG. 2 is a top view of the thermometer of the present
invention;

FIG. 3 is a front view of the thermometer of the present
invention;

FIG. 4 is a right side view of the thermometer of the present
invention;

FIG. 5 is a rear view of the thermometer of the present
invention;

FIG. 6 is a left side view of the thermometer of the present
invention; and,

FIG. 7 is a bottom view of the thermometer of the present
invention.
